United States Patent Office

Des. 192,226
Patented Feb. 13, 1962

192,226

DISH STAND OR SIMILAR ARTICLE

William M. Curtis, Painted Post, N.Y., assignor to Corning Glass Works, Corning, N.Y., a corporation of New York

Filed Feb. 10, 1961, Ser. No. 63,894

Term of patent 14 years

(Cl. D44—10)

Fig. 1

Fig. 2

FIG. 1 is a top plan view of a dish stand or similar article embodying my new design.

FIG. 2 is a side elevational view of the same.

I claim:

The ornamental design for a dish stand or similar article, as shown.
